(57) **CLAIM**

The ornamental design for a wireless microphone transmitter, as shown and described.

DESCRIPTION

FIG. 1 is a front and top perspective view of a wireless microphone transmitter, showing my new design;
 FIG. 2 is a rear and bottom perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof; and,
 FIG. 8 is a bottom plan view thereof.
 The broken lines in the figures illustrate portions of the wireless microphone transmitter that form no part of the claimed design.
